DESIGN FOR A TRACTOR CAB

Robert H. Hill, Fort Wayne, Ind.

Application November 15, 1946, Serial No. 134,811

Term of patent 14 years

(Cl. D14—3)

To all whom it may concern:

Be it known that I, Robert H. Hill, a citizen of the United States, residing at Fort Wayne, Allen County, Indiana, have invented a new, original, and ornamental Design for a Tractor Cab, of which the following is a specification, reference being had to the accompanying drawing, forming part thereof and showing my new design.

In the drawing:

Fig. 1 is a side elevational view of a tractor cab; Fig. 2 is a front elevation of the tractor cab; and Fig. 3 is a rear elevation of the tractor cab.

I claim:

The ornamental design for a tractor cab, as shown.

ROBERT H. HILL.
